(57) **CLAIM**

The ornamental design for a rear lamp cover as shown and described.

DESCRIPTION

FIG. 1 is a front elevational view of a rear lamp cover showing our new design;

FIG. 2 is a rear elevational view thereof;

FIG. 3 is an enlarged left side view thereof;

FIG. 4 is an enlarged right side view thereof;

FIG. 5 is a top view thereof;

FIG. 6 is a bottom view thereof;

FIG. 7 is a perspective view thereof;

FIG. 8 is an another perspective view thereof;

FIG. 9 is an enlarged view of portion marked as 9 in FIG. 1;

FIG. 10 is an enlarged view of portion marked as 10 in FIG. 1;

FIG. 11 is an enlarged view of portion marked as 11 in FIG. 2;

FIG. 12 is an enlarged view of portion marked as 12 in FIG. 2;

FIG. 13 is an enlarged view of portion marked as 13 in FIG. 5;

FIG. 14 is an enlarged view of portion marked as 14 in FIG. 5;

FIG. 15 is an enlarged view of portion marked as 15 in FIG. 6;

FIG. 16 is an enlarged view of portion marked as 16 in FIG. 6;

(Continued)

FIG. 17 is an enlarged view of portion marked as 17 in FIG. 7; and,

FIG. 18 is an enlarged view of portion marked as 18 in FIG. 8.

The broken lines illustrate the boundaries of the enlargements of rear lamp cover and form no part of the claimed design.

The broken lines with de-emphasized shading depict elements that form no part of the claimed design.
